UNITED STATES PATENT OFFICE.

JOHN STROOTMAN, OF BUFFALO, NEW YORK.

ARCH SUPPORT FOR SHOES.

Application filed July 12, 1924. Serial No. 725,535.

To all whom it may concern:

Be it known that I, JOHN STROOTMAN, a citizen of the United States, and residing at Buffalo, in the county of Erie and State of New York, have invented new and useful Improvements in Arch Supports for Shoes, of which the following is a specification.

This invention relates to an arch support for shoes which is separate from the shoe, so that it can be readily inserted and removed.

The principal object of the invention is the provision of a support of this character which is flexible and automatically adjustable to a high or a low heel shoe or to a high or a low arch foot.

A further object is to provide an arch support having a rigid brace which, while possessing the necessary strength and stiffness, is comparatively light.

In the accompanying drawings:

Figure 1 is a longitudinal section of a shoe containing the improved arch support. Figure 2 is a bottom plan view of the arch support. Figure 3 is a transverse section in line 3—3, Fig. 2.

Similar characters of reference indicate corresponding parts throughout the several views.

30 The improved arch support comprises a relatively soft, flexible cushion 10, of wool, felt or similar material and a rigid brace 11 secured to the underside of the cushion.

The cushion 10 rests upon the insole 12 of 35 the shoe and its outline follows the heel and shank portions of the shoe, while its upper side is concave and its lower side is shaped to conform generally to the upper side of the insole 12. The cushion preferably extends

40 from the counter of the shoe forwardly to a point short of where the ball of the foot rests, but, if desired, the cushion may be provided with an insole or facing layer 13 of felt or other suitable flexible material 45 extending forwardly some distance beyond the cushion, but not clear to the toe of the shoe. As shown, the front portions of the cushion and its facing are gradually thinned or tapered toward their front ends. The 50 facing is glued or otherwise fastened to the cushion.

The rigid brace 11 preferably consists of a comparatively short strip of metal arranged centrally and lengthwise of the cushion with its ends terminating short of the

heel and ball portions of the shoe-insole. The brace is curved longitudinally to fit the underside of the cushion and is secured thereto at or near the transverse middle portion of the brace, so as to leave its end 60 portions free and disconnected from the cushion, as shown. To render the brace strong across its attached middle portion and yet minimize its weight, it is preferably provided with laterally-extending ears 65 or enlargements 14 for the passage of fastening rivets 15 which pass through the cushion and have their heads covered by the cushion-facing 13.

By the use of such a flexible cushion and 70 a relatively short brace 11, the portions of the cushion which extend beyond the ends of the brace are capable of bending or flexing relatively to said ends to form a more or less deep or shallow arch support, thereby 75 adjusting itself to a foot with a high, low or medium arch or to a shoe with a high, low or medium heel, the detached ends of the brace permitting the contiguous portions of the cushion to slide or play on them in assuming a more or less arched form.

While permitting this self-adjusting action of the cushion, the rigid brace sustains the fallen arch bones and holds them up in place, giving comfort to the wearer. 85 At the same time, the braced cushion, which is preferably about three-eighths of an inch thick, raises the foot and draws it back in the shoe, affording, by snug lacing, about one shoe-size more room in length and width 90 for the toes and practically relieving them from all pressure and discomfort.

While performing these functions, the cushion also acts as a shoe filler or filter, serving to fill and fit the shoe when loose or 95 large at the heel or instep of the foot.

The device adds comparatively little weight to the shoe and can be readily inserted and removed.

I claim as my invention:—
 1. A self-adjusting arch support, comprising a cushion conforming to the heel and shank portions of a shoe, and a rigid brace applied to the underside of the cushion, said brace consisting of a comparatively 105 short strip extending lengthwise of the cushion and terminating short of the heel and ball portions of the shoe, the brace being secured to the cushion intermediate the ends of the brace and said ends being dis- 110

connected from the cushion, permitting the cushion, when flexed, to slide freely on the detached end portions of the brace.

2. A self-adjusting arch support, comprising a cushion conforming to the heel and shank portions of a shoe and a rigid brace applied to the underside of the cushion, said brace consisting of a comparatively short strip extending lengthwise of the cushion and terminating short of the heel and ball portions of the shoe, the brace being provided centrally with perforated laterally-projecting ears, and fastenings passing through said ears for securing the brace to the cushion, the end portions of the brace being disconnected from the cushion.

3. A self-adjusting arch support, comprising a cushion conforming to the heel and shank portions of a shoe, and a rigid brace applied to the underside of the cushion, said brace consisting of a comparatively short strip extending lengthwise of the cushion and terminating short of the heel and ball portions of the shoe, the brace being secured centrally to the cushion by rivets passing through said parts, the ends of the brace being disconnected from the cushion, and a facing secured to the upper side of the cushion and covering the heads of said rivets.

JOHN STROOTMAN.
